UNITED STATES PATENT OFFICE.

JOHN STEWART, OF GRANTVILLE, TENNESSEE.

RAIL-JOINT.

SPECIFICATION forming part of Letters Patent No. 321,655, dated July 7, 1885.

Application filed April 22, 1885. (No model.)

To all whom it may concern:

Be it known that I, JOHN STEWART, a citizen of the United States, residing at Grantville, in the county of Montgomery and State of Tennessee, have invented certain new and useful Improvements in Rail-Joints; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The object of this improvement is a rail-joint that cannot be worked loose by the expansion or contraction of the parts from heat or cold, the jars or strains produced by passing trains or other than intentional causes. These results are attained by the mechanism illustrated in the drawings herewith filed as a part hereof, in which the same letters of reference denote the same parts in the different views.

Figure 1 is a top view of a rail-joint embodying the features of my improvement. Fig. 2 is a side elevation of the same. Fig. 3 is a top view of one of the parts previous to its application in forming the joint. Fig. 4 is a view of the same part in an advanced stage of its application. Fig. 5 is an enlarged top view of one of the parts detached. Fig. 6 is a vertical transverse section of the same, taken on the line $x x$.

$A A'$ indicate sections of rails. $B B B B$ represent a series of split keys having eyes B' inserted, while in the form shown in Fig. 3, through correspondingly-formed slots in the rails $A A'$ and fish-plates $C C'$, after which their ends are bent apart from each other, substantially in the manner shown in Fig. 4, for the reception of a wedge-shaped metal piece, E , having lateral projections, e , extending partially over the divisions of the keys B , for a purpose hereinafter set forth. After the keys B are inserted through the slots in the fish-plates $C C'$ and rails $A A'$ their ends

are separated by means of a fuller or other suitably-formed tool being forced between the parts, while a stake or other suitable bearing 50 appliance is held against their eyes B' , and the wedge-shaped pieces E are set and forced between them as far as they will go and secured in such position by bending the ends of the keys B over their corners, as shown at 55 B^2 , Fig. 1. The eyes B' will operate as bolt-heads, and, driving the wedges E between the divisions of the keys, will draw the fish-plates $C C'$ and the rails $A A'$ tightly together, and, bending the ends of the keys over 60 the corners of the wedges, will secure the rigidity of the joint against change, except by bending back the divisions of the keys B and removing the wedges E .

One of the objects of providing the keys 65 with the eyes is for facilitating the removal of the keys should it be necessary to remove and replace the rails. The ends of the keys adjacent to the wedges E would first be disconnected therewith and made as nearly 70 straight as practicable by hammer and stake or other suitable appliances, when blows upon a mandrel or other tool inserted through the eyes B' would rapidly disengage the keys from the rails and fish-plates. The lateral projections e on the wedges E will prevent them 75 from dropping through the divisions of the keys, in which event the strains and jars caused by passing trains would have a tendency to press the divisions of the keys together, and thereby loosen the joint.

Having explained the construction and operation of my improvement, what I claim as new, and desire to secure by Letters Patent, 80 is—

The keys B and wedges E , in combination with the fish-plates and rails, substantially as specified, for the purpose set forth.

In testimony whereof I affix my signature in presence of two witnesses.

JOHN STEWART.
